UNITED STATES PATENT OFFICE.

CHARLES J. WALLEN, OF CLEVELAND, OHIO.

RATCHET-WRENCH.

1,204,095.

Specification of Letters Patent.

Patented Nov. 7, 1916.

Application filed July 10, 1916. Serial No. 108,413.

To all whom it may concern:

Be it known that I, CHARLES J. WALLEN, a citizen of the United States, residing at Cleveland, in the county of Cuyahoga and 5 State of Ohio, have invented certain new and useful Improvements in Ratchet-Wrenches, of which the following is a specification.

This invention relates to an operating lever or handle adapted particularly for 10 use in connection with the winding shafts of dump cars or the like, although capable of use on jacks and other power devices. These articles are usually known as "wrenches," and the object of the invention 15 is to provide a safety device of the kind, by the use of which it is impossible for the operator to get hurt.

The invention is particularly directed to the means for holding the pawl of the lever 20 engaged with the ratchet, and for releasing the same therefrom to permit the free turn of the ratchet wheel shaft, said means in the present embodiment comprising a locking lever by the operation of which the pawl 25 is advanced or retracted.

In the accompanying drawings: Figure 1 is a side elevation of the device. Fig. 2 is 30 a detail in elevation with a face plate removed, showing the pawl and its operating lever. Fig. 3 is a detail in section showing a lug on the side of the lever, which acts to release the detent which normally engages the ratchet wheel on the shaft.

Referring specifically to the drawings, 35 indicates a squared opening in a ratchet wheel 7 mounted to turn in a head 8 of the wrench, in a manner common in this class of devices. This opening receives the squared end of the shaft to which power is 40 to be applied. The handle 9 constitutes a lever for turning the ratchet wheel and the shaft engaged thereby. The handle and head of the wrench are recessed as indicated at 10 to form a housing for a pawl 11, 45 the toe of which may be advanced to engagement with the teeth of the ratchet as shown in Fig. 2, or retracted therefrom to release the ratchet. The pawl has spaced lugs 12 and 13 which are engaged by a lug 50 14 projecting from a lever 15 which is pivoted at 16 in the body of the wrench, and swings in or out to retract or advance the pawl. A loop or latch 17 is pivoted to the

handle and is adapted to swing over the end of the lever 15 and lock the same with the 55 pawl in advanced position, as shown in Fig. 1. On one side of the lever is a lug 18 projecting laterally in position to strike and lift the usual detent 20 which normally engages a ratchet 21 on the winding shaft 80 indicated at 22.

To lock the wrench to the winding shaft, for operating the latter, the pawl is advanced by swinging in the lever 15 and locking the same to the handle by the latch 17, 65 and in this position the wrench may be swung around by the operator to turn the ratchet wheel and the shaft engaged thereby. To release the wrench, and permit the shaft to run free, the latch 17 is released, 70 and a spring 23, bearing under the lever 15, lifts the same and retracts the pawl from engagement with the ratchet, and the latter is then free to turn with the shaft.

When the wrench is mounted on the 75 shaft, as previously described, and operated as indicated, the lug 18 acts by contact with the detent 20 to lift the latter from engagement with the ratchet 21 thereby permitting the shaft to run free, without lifting 80 the detent by hand in the usual manner.

In either position, therefore, there is no possibility of accidental engagement or disengagement of the pawl with the ratchet wheel, which, in devices of this kind, is apt 85 to work injury to the operator.

What I claim as new is:

1. The combination with a ratchet wheel, handle, and a sliding pawl carried by the handle and engageable with the wheel, of 90 a lever pivoted on the handle, said pawl having a projection engaged by the lever to advance or retract the pawl.

2. The combination with a ratchet wheel and handle, of a sliding pawl carried by 95 the handle and engageable with the wheel, said pawl having lugs, and an operating lever for the pawl, pivoted to the handle, and having a projection engaging between said lugs to advance or retract the pawl. 100

In testimony whereof, I do affix my signature in presence of a witness.

CHARLES J. WALLEN.

Witness:

JOHN A. BOMMHARDT.
